UNITED STATES PATENT OFFICE.

EMIL NORDWALL, OF LA GRANGE, ILLINOIS.

DAMPER.

1,278,987.

Specification of Letters Patent. Patented Sept. 17, 1918.

Application filed December 26, 1917. Serial No. 208,722.

To all whom it may concern:

Be it known that I, EMIL NORDWALL, a citizen of the United States, residing at La Grange, in the county of Cook and State of Illinois, have invented certain new and useful Improvements in Dampers, of which the following is a specification.

My invention relates to improvements in dampers.

10 One of the objects of my invention is to provide an improved damper and means for operating same to regulate the draft from a fireplace, or the like.

A more specific object of my invention is 15 to provide damper operating means, located in front of the fire place or grate, and readily accessible for operation whereby to move the damper to the desired extent for regulating the draft by throttling or entirely closing the throat of the chimney 20 through which the products of combustion pass.

Other and further objects of my invention will become readily apparent to persons skilled in the art, from a consideration 25 of the following description when taken in conjunction with the drawings, wherein:—

Figure 1 is a front elevation of a fire place or grate showing the damper operating handle.

Fig. 2 is a section taken on line 2—2 of Fig. 1.

Fig. 3 is a section taken on line 3—3 of Fig. 2.

35 Fig. 4 is a similar enlarged section of a fragment.

Fig. 5 is a perspective view of the damper.

In all the views the same reference characters are employed to indicate similar parts.

40 Heretofore damper operating means have been located inside of the fire place and when it is desired to open and close the damper it has been necessary to reach up into the fire place and move the damper, or the arm 45 or lever connected thereto. There is usually a latch or lever connected to the damper which can only be manipulated by contact with the hand. Such latch is always covered with soot and when the fire is burning in the grate the manipulation of the damper is 50 exceedingly difficult and uncomfortable.

55 My damper operating handle is located in front of the fire place and is so arranged that the extent to which the damper has been opened is readily indicated by the position of the handle.

In the drawings which I have employed disclosing the character of my invention, 10 is a chimney having a flue 11 and a fire place 12. The throat 13 is adapted to be closed 60 by a damper 14 which is pivoted at 15 and 16.

The damper 14 is preferably a plate having a projecting trunnion 17 at one end and an inner trunnion 18 at the other end. The 65 trunnion 18 does not project beyond the end 19 of the damper, and on either side of the trunnion is a slot 20 and 21, within which to receive the bearing sleeve 22. The projecting trunnion 17 is located in a bearing 70 sleeve 23. The sleeve 22 is axially moved in an opening 24 made in the side wall 25 of the chimney. In placing the damper in position the trunnion 17 is first inserted in the sleeve 23, after which the other end 75 of the damper is brought up in axial position with the sleeve 22 and the latter is drawn out of the socket 24 and may be held in that position by application of cement, or otherwise. A part of the damper is cut away 80 at one end from the edge 25 to provide space for the operating rod 26. An arm 27 is pivoted to two lugs 28 and 29 which form, preferably, integral parts of the damper plate 14, and is provided on its outer end 85 with an opening 30. An arm 31, is secured on the square rod 26 and is provided with a reduced end 32 which projects through the opening 30 for sliding engagement with the arm 27 for the purpose of operating the 90 damper. The rod 26 is provided with a bearing sleeve 33, which is insertible in the rear wall 34 of the chimney, and with another bearing sleeve 35 insertible in the front wall 36. A handle 37 is connected to the front 95 end of the rod 26 and is spaced away from the front surface of the wall 36 by a plate 38, which preferably forms a part of the bearing sleeve 35.

The damper 14 always preserves a relative 100 position with the handle 37, so that the location of the handle will determine the extent to which the damper closes the throat 13.

My damper regulator is very convenient to be used as a means of ventilating the 105 room, in which the grate is located, even when the room is heated by other means, as for instance by hot air furnace, hot water or steam plants. The extent to which the damper is open will determine the amount 110 of used or vitiated air that will be taken from the room, by the draft of the chim-

ney, thereby enhancing the value of the air by frequent renewal with fresh air in the apartment.

While I have herein shown and disclosed a single embodiment of my invention it will be evident that changes may be made in the structure within the scope of the appended claim.

Having described my invention, what I claim is:

In combination with a chimney having a fire place flue and throat, of a damper for insertion at the throat of a fire-place flue comprising a plate having two trunnions one

at each end, one projecting beyond the end 15 of the damper; sleeves insertible in the chimney to provide bearings for the trunnions; a rod passing through the throat of the chimney, at right angles to the axis of the damper; a handle on the front end of the 20 rod to operate the damper; an arm on the rod, and an arm pivoted to the damper and having a hole in its free end through which the first mentioned arm passes to transmit motion from the rod to the damper.

In testimony whereof I hereunto set my hand.

EMIL NORDWALL.
